UNITED STATES PATENT OFFICE.

JOHN W. ENRIGHT, OF NEW ORLEANS, LOUISIANA.

STATIONARY CHEMICAL-MIXING FIRE-EXTINGUISHING SYSTEM.

Application filed October 7, 1920. Serial No. 415,275.

To all whom it may concern:

Be it known that I, JOHN W. ENRIGHT, a citizen of the United States of America, residing at New Orleans, in the parish of Orleans and State of Louisiana, have invented certain new and useful Improvements in Stationary Chemical-Mixing Fire-Extinguisher Systems, of which the following is a specification.

10 This invention relates to a stationary chemical-mixing fire-extinguisher system.

The invention relates to a system which is devoid of moving mechanical parts and operates automatically under fire emergency 15 conditions and the objects of the invention are to insure the prompt and certain automatic operation of the system and to insure a regular and continuous supply of acid to the alkaline solution, thereby providing for 20 the discharge of substantially the entire volume of alkaline solution at a substantially uniform pressure.

In the illustrative embodiment of the invention shown in Fig. 1 the system includes 25 the usual tank 1 for an alkaline solution, and a riser 2 extending from said tank throughout the height of the building, and in the embodiment disclosed, is connected at its upper end to a distributing system including 30 a reservoir 15, in turn connected to the upper end of a standpipe 18 from which extend the leaders or laterals 16 carrying the sprinkler heads 17. The reservoir 15, standpipe 18 and leaders or laterals 16 are 35 filled with an extinguishing liquid, preferably of a non-freezing variety, and the lower end of the standpipe 18 projects into a reservoir 6 containing mercury. The system also includes a reservoir 5, which connects to the reservoir 6 by a pipe 19, the pipe 19 extending into the mercury in the reservoir 6. The system also includes a primary acid receptacle 4, which is preferably arranged in an extension 7 of the tank 1, located 40 at its upper side thereof. The primary acid receptacle 4 encloses an acid discharge siphon pipe 13 projecting externally of said receptacle and discharging into the tank 1, the amount of acid discharged from 45 the primary acid receptacle being sufficient to generate the initial working pressure.

The system also includes a secondary acid receptacle 3 which encloses a discharge pipe 8 discharging at its upper end into the tank 1.

50 The air spaces in the primary and second-

ary acid receptacles normally have free and unrestricted communication with the air space in the tank 1 for preventing pressure differences between the air space in the tank 60 and the air spaces in the primary and secondary acid receptacles. This communication consists of a pressure equalizing pipe 9 having a downturned limb 10 and branches 11 and 12 which form a trap for a liquid 65 seal, under fire emergency conditions as will be explained later. At its upper end the pipe 9 is connected to the reservoirs 5 and 6, by a bent conduit forming a trap 14.

After the tank 1 has been filled with the 70 requisite amount of alkaline solution and acid has been placed in the primary receptacle 4 and secondary receptacle 3, and mercury has been placed in the reservoir 6, the reservoir 15, the stand-pipe 18 and leaders or laterals 16 are filled with extinguishing 75 liquid. The weight of this liquid is effective to displace the mercury in the reservoir 6, i. e., to force a column of mercury into the trap 14. The reservoir 5 thereupon 80 is filled with the liquid, and the system is now ready for operation.

When a sprinkler head 17 is opened under fire emergency conditions, the extinguisher liquid in reservoir 15 is discharged and the 85 pressure on the mercury in the reservoir 6 is relieved with the result that the mercury column recedes from the trap 14, allowing the liquid in the reservoir 5 to flow through the trap 14 into the pipe 9, and entering 90 the pipes 11 and 12 in which it is trapped, hermetically sealing the communication between the air spaces of the receptacles 3 and 4 and the tank 1. The liquid flowing into the trap formed by the pipes 9, 11 and 12 95 rises in the pipe 12 and compresses the trapped air in the primary acid receptacle creating a pressure sufficient to initiate the siphoning of acid from the primary receptacle. The high pressure gases generated 100 in the solution tank consequent to the mixing of the chemicals passes through the pipe 10 to the liquid seal in the trap formed by the pipes 9—12 and acting upon this seal equalizes the pressure in the primary 105 receptacle with the pressure in the tank 1, thus insuring an uninterrupted siphoning of acid from the primary acid receptacle. The high pressure gases generated consequent to the mixing of the chemicals in the 110 solution tank, also passes through the pipe 8 to the receptacle 3 in which it is trapped

by the liquid seal in the pipes 9 and 11 and becomes effective to eject acid from the secondary acid receptacle, as soon as the pressure in the tank falls below the trapped 5 pressure in the secondary acid receptacle. In this way the operation of the system is maintained continuously and at a substantially uniform rate of pressure.

Having fully described my invention, I 10 claim:-

1. In a chemical mixing fire extinguisher system, a carbonate solution tank, an acid receptacle positioned in operative relation to said tank having the upper part thereof 15 closed to form an air chamber, a siphon affording communication between said receptacle and said tank, a pressure equalizing pipe communicating with said tank and having an upwardly turned branch com- 20 municating with said air chamber, said pipe normally being open throughout its length for balancing the pressure on both sides of the body of acid in said receptacle, but adapted upon occasion to receive and sus- 25 tain an unbalancing liquid column, an ele- 30 vated reservoir normally containing sufficient liquid to form said unbalancing column, a pipe having an upward bend connecting said reservoir and pressure equalizing pipe, said bend being normally filled with mercury forming a seal, a distributing system including a stand pipe communicat- 35 ing with said mercury seal and maintaining the level of the mercury therein suffi- 40 ciently high to prevent discharge of the liquid contained in said reservoir into said pressure equalizing pipe, a sprinkler head communicat- 45 ing with said distributing system, said mercury seal being lowered, upon the depletion of the column of liquid in said distributing system through 50 said sprinkler head, sufficiently to permit discharge of the liquid from said reservoir into said pressure equalizing pipe, forming an unbalancing column of sufficient height to initiate the siphonic discharge of acid from said acid receptacle into said carbonate solution tank.
2. In a chemical mixing fire extinguishing system, a carbonate solution tank, primary and secondary acid receptacles positioned in

operative relation to said tank, and having the upper parts thereof enclosed to form air chambers, a siphon affording communication between the primary acid receptacle and said tank, a pressure equalizing pipe 55 communicating with said tank and having upwardly turned branches communicating with the respective air chambers of said acid receptacles, said pipe normally being open throughout its length for balancing 60 the pressure on both sides of the bodies of acid in said receptacles, but adapted upon occasion to receive and sustain an unbalancing liquid column for initiating the siphonic discharge of acid from the primary 65 acid receptacle into the carbonate solution tank, a discharge pipe for the secondary acid receptacle opening within said receptacle below the normal liquid level therein and terminating within the carbonate solution 70 tank externally of said secondary acid receptacle at a sufficient height to defeat the initiation of siphonic flow therethrough by said unbalancing column, an elevated reservoir normally containing liquid to form said 75 unbalancing column, a pipe having an upward bend connecting said reservoir and pressure equalizing pipe, said bend being normally filled with mercury forming a seal, a distributing system including a stand pipe 80 communicating with said mercury seal and maintaining the level of mercury therein sufficiently high to prevent discharge of the liquid contained in said reservoir into said pressure equalizing pipe, a sprinkler head 85 communicating with said distributing system, the level of said mercury seal being lowered, upon the depletion of the column of liquid in said distributing system through said sprinkler head, sufficiently to permit 90 discharge of the liquid from said reservoir into said pressure equalizing pipe, forming therein the unbalancing column of liquid.

In testimony whereof I have hereunto set my hand in presence of two subscribing witnesses.
